GAS PILOT AND BURNER

Filed March 23, 1929

By his Attorneys Irving M. Austin

Darby & Darby

UNITED STATES PATENT OFFICE

IRVING M. AUSTIN, JR., OF RYE, NEW YORK

GAS PILOT AND BURNER

Application filed March 23, 1929. Serial No. 349,346.

This invention relates to gas pilot and, in particular, to gas pilots used in connection with gas burners whereby the burner is ignited without the loss of gas in the open air.

5 A further object of my invention includes a pilot construction which is simple and cheap of manufacture, efficient in operation to guard against accidental escape of unignited gas, and which will always be in position to operate for igniting gas whenever gas is supplied to the burner in varying quantities.

A further object includes the provision of by-pass means in the gas supply and regulating fixture whereby the pilot is maintained 15 at low pressure when the gas regulating cock is turned off, but said pilot is supplied with additional gas when the gas regulating cock is turned on to supply gas to the burner.

The location of the pilot construction is 20 such as to be in close proximity with the gas burner plate so as to apply the pilot flame over the burner plate at the time or, immediately before the plate is supplied with a flow of gas. The pilot housing, or shield, is 25 of specific construction so as to supply a Bunsen burner effect to the pilot and protect the pilot flame against accidental extinguishing as will be more fully set forth hereinafter.

Other objects will appear hereinafter and 30 I obtain these objects by the construction illustrated in the accompanying drawings, in which

Figure 1 is a plan view of a gas burner with a pilot of my improved construction;

35 Fig. 2 is a side view thereof partly in section;

Fig. 3 is a horizontal section of the gas and pilot connection and showing the gas regulating plug in closed position;

40 Fig. 4 is a vertical section of the gas and pilot connection showing the gas regulating plug partly in section;

Fig. 5 is a vertical section of the fixture shown in Fig. 3 showing the gas regulating 45 plug in intermediate position; and

Fig. 6 is a sectional view of the tip end of the pilot pipe.

Like numerals of reference refer to the same parts throughout the several views.

50 It is among the prime objects of my in-

vention to provide a pilot construction for gas plates which is so constructed and located as will effectively prevent the escape of unconsumed gas at any time, either during the operation of the burner, or before the 55 gas is turned on fully. The pilot, moreover, is operated from the common gas fixture which supplies the gas to the burner and to the pilot thereby facilitating operation and greatly reducing the accidental dangers of 60 applying a pilot flame to a gas burner at the wrong moment so as to flare back or not ignite the gas burner at all. It will be noted that the relation of the pilot to the burner and the mechanism for turning on the gas 65 to the burner is such that at no time will there be any opportunity for unconsumed gas to escape from the burner. This is by reason of the position of the pilot, its specific construction and its inter-relation 70 between the gas regulating feed for the burner and the gas regulating feed for the pilot, all as will appear more fully hereinafter.

Referring now to the drawing in which is 75 shown a specific form of construction without thereby intending to limit said construction to the exact showing, the usual gas burner 10 is supplied with the conducting tube 11 and flared end 12 for providing passage and mixing space for the gas and air as is well known in the art. This construction is supplied with a gas cock or gas fixture 13 connected directly into the gas supplying pipe 14. The relation of these parts is of 80 the known construction.

The gas fixture, or cock, 13, however, is so 85 constructed as to provide means whereby a pilot flame is constantly present in the pilot housing which flame becomes active at the proper moment when gas is supplied to the burner.

One form of construction for accomplishing the aforesaid objects in this respect resides in the provision of a pilot pipe 15 of 90 suitable dimensions and shape so as to provide means for conducting a supply of gas to the pilot in the pilot housing or shield 19. The pilot pipe is fitted into the fixture in a pilot bore 17 of suitable diameter and is held 95 100

in position by any suitable means such as a nut 16.

The pilot housing or shield located at the pilot end of pipe 15 comprises an enlarged substantially pear-shaped construction having an opening 20 at the bottom thereof and being provided with a pilot mouth 21 opposite the pilot plug 18. The mouth itself is protected by an overhanging shield 22 whereby the pilot flame is protected against accidents which might cause the flame to be blown out, or otherwise extinguished by steam or water from a cooking vessel when the burner is used.

15 It will be noted that the pilot housing 19 and the pilot flame itself will occupy the housing under normal conditions, that is, when the pilot is supplied with a minimum of gas. At the instant, however, when the 20 gas supply is increased the pilot flame will shoot out of the mouth and across the face of the gas plate to ignite the gas the moment that it is supplied. This supply is accomplished in the following manner.

25 The gas fixture 13 is provided with a gas regulating plug 23 of standard construction having a handle 24. Said plug is provided with a bore 25 of suitable diameter and so positioned that it will control the pilot bore 30 17 of the gas fixture and also the bore 26. It will be noted that the diameters of bores 25 and 26 are substantially equal and that the location of the pilot bore 17 is such as to be open to gas pressure as the pilot regulating plug is turned into open position to feed gas to the burner. The closed position of the fixture is shown in Fig. 3 and its intermediate position in Fig. 5. This arrangement provides for an igniting flame in the 40 pilot which is always in proper position over the burner at the instant when gas is supplied to the burner. It will be noted by this arrangement that gas pressure is also supplied to the pilot when the burner is turned 45 low thereby guarding against accidental extinguishing of the gas under low pressure. The gas fixture 13 is provided with a pilot by-pass 27 which may be regulated by a regulating screw 28 as is shown in Figs. 3 and 5.

50 A gas injection nozzle 29 is supplied at the end of the gas fixture 13 and this nozzle is provided with a restricted passage 30 for supplying gas in suitable quantities to accomplish the Bunsen effect in the usual manner. The burner 10 may be supported in the usual way as by a rod 31 and it is understood that the principle and relationship of burner and my improved pilot is applicable wherever used in connection with gas plates or 60 gas heaters for cooking, heating or for other purposes.

From the description and disclosure thus far given it is apparent that my apparatus can be readily applied to the usual types of 65 gas fixtures and that the same is operable

by the mere turning of handle 24 into closed or open position as is ordinarily done in gas stoves. By addition of my improved fixture and pilot all danger of accidental escape of unconsumed gas is avoided.

Various modifications will, undoubtedly, suggest themselves to those versed in the art without departing from the spirit and scope of my invention as disclosed and as herein claimed. I, therefore, do not desire to restrict myself to the specific showing.

What I claim as new and useful, therefore, is:

In a gas burner and pilot therefor located near the burner, a gas cock connected to the burner for controlling the supply of gas thereto, said gas cock comprising a body portion and a movable member with a bore therethrough, the body member having a pilot gas feeding bore connected to the pilot and a by-pass connecting the pilot bore with the gas supply side of the cock, the relative size and position of the bore in the movable element and the pilot bore being such that the supply of gas to the pilot is greatly increased just before and at the time gas is supplied to the burner which supply of gas to the pilot is decreased as the supply to the burner is increased through the movable element of the cock.

In testimony whereof I have hereunto set my hands on this 18th day of March A. D. 1929.

IRVING M. AUSTIN, JR.
